UNITED STATES PATENT OFFICE.

DANIEL C. MULVIHILL, OF HANNIBAL, MISSOURI, ASSIGNOR TO HANNIBAL CAR WHEEL & FOUNDRY COMPANY, A CORPORATION OF MISSOURI.

FOUNDRY APPARATUS.

Application filed June 1, 1920. Serial No. 385,631.

To all whom it may concern:

Be it known that I, DANIEL C. MULVIHILL, a citizen of the United States, and resident of Hannibal, county of Marion, and State 5 of Missouri, have invented certain new and useful Improvements in Foundry Apparatus, of which the following is a specification, and which are illustrated in the accompanying drawings, forming a part thereof.

10 The invention relates to foundry apparatus and has as an object the provision of apparatus for casting a large number of like objects whereby the formation of the molds, pouring of the metal, shaking out and reuse 15 of the flasks is a continuous operation.

An illustrative embodiment of the invention as applied to the manufacture of car wheels is shown in the accompanying drawings, in which;

20 Fig. 1 is a plan view of the complete apparatus;

Fig. 2 is a detail section on line 2—2 of Fig. 1, showing a crane in elevation;

25 Fig. 3 is a detail section on line 3—3 of Fig. 1;

Fig. 4 is a detail section of air connections taken on line 4—4 of Fig. 2, omitting the jacks;

30 Fig. 5 is a detail plan view of the connections between the wheels;

Fig. 6 is a detail plan view showing one of the propelling jacks, and

35 Fig. 7 is a detail elevation of the turntable showing a completed mold in section.

To provide the desired continuous operation there is indicated a circular two-rail track 10, made of T rails preferably laid in a trench 11, which may be lined with concrete, as shown at 12, Fig. 2. Mounted on

40 the track 10 there is shown an annular turntable 13, preferably comprising a series of flanged car wheels 14 arranged in pairs, each pair assembled on an axle 15 and one wheel of each pair upon each of the rails

45 of the track 10. To preserve the spacing of the pairs of wheels and to cause the turntable to revolve as an entity there are shown links 16 which may be slipped over the ends of the axles 15 and may be retained thereon, as by a collar 17. To make it possible to

50 remove any wheel without tearing down any large part of the turntable, the wheels 14 are shown assembled with their flanges on the outside of the rails.

A simple form of turntable top may be 55 constructed, as shown, by providing two concentric circles of inverted T rails 18, which may be connected by cross plates 19. If desired braces 20 may also be supplied to more perfectly preserve the relative position 60 of the rings. The rings of T rails 18 are shown as resting directly on the edges of wheels 14 and when so constructed and applied will require no supporting frame. The drags 22, as well as the assembled 65 flasks 23 are shown as resting on the upturned bases of the rails 18 comprising the rings of the table top.

To cause motion of rotation of the turntable 13 there are shown two motors 24 and 25 which may be controlled by a single valve 26. The motors 24 and 25 are indicated as single stroke fluid pressure motors, each comprising a cylinder and piston. When fluid under pressure as water, air or steam 70 is admitted through pipes 27, 28 and 29, to the rear end of the cylinders, the piston will be forced outwardly. When the pressure is admitted to the forward ends of the cylinders through pipes 30, 31 and 32, the 75 pistons will be retracted. A source of fluid pressure is indicated at 33 connected to valve 26 by pipes 34, 35.

The piston rod 36 of motor 24, which may be similar to motor 25, is shown in Fig. 6, as 85 bearing a pawl head 37 traveling in ways 38. A pawl 39 held in position by spring 40 is shown as coacting with studs 41 secured to the outer ring of T rails 18. As the pistons of motors 24 and 25 are retracted 90 the pawls will slip past one stud 41 and upon the forward stroke the two motors will act together to revolve the entire turntable. Preferably, the studs 41 are spaced the desired distance on centers of the copes and 95 flasks as they lie upon the table. The springs 40 are not stiff enough to cause any movement of the table in a reverse direction.

A four armed revolving crane 41 is shown 100 for handling the drags 22 and a like crane 42 for handling the copes 21. As shown more in detail in Fig. 2, these cranes comprise an upright 43, pivoted at top and bottom and the arms 49, each constitute a track for a carriage 44 from which a pneumatic lifting jack may be suspended. To operate the jacks an air line 45 is shown leading to the

bottom of the upright then upwardly in the center as at 46. The pipe 46 is not mounted to revolve but as shown in Fig. 4 a connection 47 may be fitted to the upper end of 5 the pipe 46 by means of a stuffing box 48, so that the connection 47 may revolve with the arms 49.

The top of the connection 47 is shown as supplied with a double T 50 to each branch 10 of which a flexible air hose 51 may be secured, each of which in turn is connected to one of the jacks 52.

The copes 21 are preferably delivered to the sanding station 53 by means of a gravity 15 conveyor 54, while the drags are shown as delivered within reach of crane 41' by the turntable 13. The cranes 41' and 42 are turned in the direction of the arrows by the hands of the workmen. A drag is picked 20 up by crane 41' and swung to the sanding position 55. At the same time a drag containing a finished impression is swung to the turntable and deposited and an empty drag is picked up by the arm last reaching 25 the table. At the next movement of the crane the first drag mentioned will be deposited full of sand upon the jolting table 56, next to the finishing position 57 and in turn will be deposited upon the turntable. 30 Thus it will be seen that the process of filling a drag with sand, condensing the sand in a drag, and finishing the impression left by a pattern is being conducted upon three drags at the same time while a fourth 35 is being deposited upon the turntable and an empty drag is being hung upon the crane.

The action of crane 42 and the formation 40 of an impression in a cope is carried on in exactly the same manner except that the copes are delivered to the sanding position 53 by the conveyor 54 and the arm of the crane is empty while moving from the turntable to the sanding position. The workmen at the junction of the turntable and the crane 42 do not have to attach an empty 45 cope to the crane but they may use the time that would be taken by so doing, in clamping together the complete flask after placing 50 the cope containing the impression upon the drag deposited by crane 41. The cores will be placed by the workmen at the turntable and crane 42 or by others between the two cranes as seems most convenient.

55 For applying the metal there is shown a pouring station comprising a cupola at 58, a mixing ladle at 59 and a pouring ladle at 60. The castings being poured from ladle 60 will have the time required by the 60 turntable in revolving from the pouring station to the "shaking out" station 61 in which to harden sufficiently to be removed from the molds. This shaking out station could be spaced a greater portion of the 65 circumference of the turntable away from

the pouring station if it is found desirable to allow more time for cooling. The position shown is found to be convenient as a location for the used sand and for release of the copes to be returned by conveyor 54. 70 To lift the flasks and castings from the turntable there is shown a jib crane 62. A traveling crane is indicated at 63 which may be utilized to remove castings or to bring in fresh supplies of sand. 75

For handling of sand a second jib crane 64 is indicated which may handle the sand by means of a clam shell bucket 65. By means of the crane and bucket the used sand may be deposited in a sand pit 66. 80 where it may be prepared for use and also by use of the crane and bucket it may be moved from the pit to bins 66, 67, for delivery by gravity to the sanding stations 53, 55. 85

I claim as my invention:

1. In foundry apparatus, in combination, a turntable, adapted to convey flasks to various stations arranged about its periphery, a revolving crane having a plurality of arms 90 adapted to deliver flask parts containing completed impressions to the turntable and a plurality of positions each having apparatus adapted to perform part of the operation of making a completed impression in 95 a flask part, said positions each being within the reach of the arms of the revolving crane.

2. A foundry apparatus comprising, in combination, a turntable adapted to convey 100 flasks, a pouring station, a shaking out station and a molding station arranged about said turntable, means to turn said table, a revolving crane at said molding station, said crane having a plurality of arms adapted to 105 deliver completed molds to said turntable, a plurality of positions within reach of said revolving crane, each position having apparatus to perform part of the operation of producing a completed mold. 110

3. A foundry apparatus comprising, in combination, a turn-table, pouring, shaking out, drag molding and cope molding stations arranged about said turn-table, a conveyor adapted to convey empty copes from said 115 shaking out station to said cope-molding station, means at the shaking out station to return empty drags to the turn-table, and means at the drag-molding station to remove empty drags from the turn-table. 120

4. A foundry apparatus comprising, in combination, a turntable, pouring, shake out, drag molding and cope molding stations arranged about said turntable, a conveyor adapted to convey empty copes from said 125 shaking out station to said cope molding station, a revolving crane at said cope molding station having a plurality of arms, a plurality of positions within reach of said arms, apparatus at each of said positions to 130

perform part of the operation of forming a mold in a cope, said arms adapted to deliver completed molds to said turntable.

5. A foundry apparatus comprising, in combination, a turntable, pouring, shake out drag molding and cope molding stations arranged about said turntable, a revolving crane at each molding station, each crane having a plurality of arms, a plurality of 70 positions within reach of the arms of each of said cranes and apparatus at each of said positions to perform part of the operation of forming a mold in a drag or a cope.

10. A foundry apparatus comprising, in combination, a circular track comprising concentric rings or rails, a turntable comprising spaced pairs of wheels resting on said rails, an axle connecting each pair of wheels, links connecting the axles, a second 75 pair of concentric interconnected rings, molding flasks carried directly upon said last-named rings, such rings resting directly on the periphery of said wheels, means for causing intermittent movement of said turntable, and molding and pouring apparatus adjacent said turntable.

15. A foundry apparatus comprising, in combination, a circular track, a plurality of pairs of wheels resting on said track, each 80 pair connected by an axle, links connecting the axles to preserve their spacing, concentric rigidly interconnected rings resting on said wheels, radially projecting lugs on the outer of said rings, a plurality of single 85 stroke reciprocating motors adjacent the outside of said outer ring, pawls actuated by said motors to coat with said lugs on one stroke of the motors and a common valve for controlling the movements of said 90 motors.

20. A foundry apparatus comprising, in combination, a turntable, pouring, shake out, drag molding and cope molding stations arranged about said turntable, and a conveyor 95 located within the circumference of the turntable and adapted to convey empty copes from said shaking out station to said cope molding station.

25. A foundry apparatus comprising, in combination, a turntable, pouring, shake out, drag molding and cope molding stations arranged about said turntable, and a conveyor located within the circumference of the turntable and adapted to convey empty 100 copes from said shaking out station to said cope molding station, and means also located within the said circumference for returning empty drags to the turntable to be conveyed to the drag molding station.

30. A foundry apparatus comprising, in combination, a turntable adapted to convey flasks, pouring, shake out, drag molding and 105 cope molding stations arranged about said turntable, a conveyor located within the circumference of said turntable and adapted

to convey empty copes from said shaking out station to said cope molding station, a revolving crane at said cope molding station having a plurality of arms, a plurality of 70 positions within reach of said arms, apparatus at each of said positions to perform part of the operation of forming a mold in a cope, said arms being adapted to deliver completed molds to said turntable.

35. A foundry apparatus comprising, in combination, a turntable, adapted to convey flasks to various stations arranged about its periphery, pouring, shake out, drag molding and cope molding stations arranged about said turntable, a revolving crane at 80 each molding station, each crane having a plurality of arms, a plurality of positions within reach of each of said cranes and apparatus at each of said positions to perform part of the operation of forming a 85 mold in a drag or cope.

40. A foundry apparatus comprising, in combination, a circular track comprising rings or rails, a turntable comprising spaced 90 pairs of wheels resting on said rails, an axle connecting each pair of wheels, links connecting the axles, concentric rigidly interconnected rings for directly carrying molding flasks, such rings resting directly on the periphery of said wheels, means for causing 95 intermittent movement of said turntable for conveying said flasks to various stations, and a revolving crane located within the circumference of the turntable and having a plurality of arms adapted to deliver flask 100 parts to the turntable.

45. A foundry apparatus comprising, in combination, a circular track comprising rings or rails, a turntable comprising spaced 105 pairs of wheels resting on said rails, an axle connecting each pair of wheels, links connecting the axles, concentric rigidly interconnected rings for directly carrying molding flasks, such rings resting directly on the periphery of said wheels, means for causing 110 intermittent movement of said turntable for conveying said flasks to various stations arranged about its periphery, a revolving crane having a plurality of arms adapted to deliver flask parts containing completed impressions to the turntable, and a plurality of positions each having apparatus adapted to perform part of the operation of making a completed impression in a flask part, said 115 positions each being within the reach of 120 the arms of the revolving crane.

50. A foundry apparatus comprising, in combination, a circular track comprising concentric rails located within a trench, a turn table comprising spaced pairs of flanged 125 wheels resting on said rails with their flanges on the outside of the rails, an axle connecting each pair of wheels, detachable links connecting adjacent axles, and a pair of concentric rings for directly carrying molding 130

flasks, such rings resting directly on the peripheries of said wheels.

15. A foundry apparatus comprising, in combination, a circular track comprising 5 concentric rails, a turn table comprising spaced pairs of flanged wheels resting on said rails with their flanges on the outside of the rails, and a pair of concentric rings for directly carrying molding flasks, such rings 10 resting directly on the peripheries of said wheels.

16. A foundry apparatus comprising, in combination, a turn table comprising spaced 15 pairs of wheels, a pair of concentric inter-connected rings resting directly on said

wheels, lugs projecting from one of said rings, and means adapted to engage said lugs for imparting intermittent rotation to said turn table.

17. In an equipment for foundries and the 20 like, the combination of a closed track or way circuit, carriers therein, means for moving said carriers progressively about said circuit with a step by step advance and past molding, pouring and cooling stations 25 and past also a product removing or shake-out station, and independent gravity means for returning the flask parts to said molding station.

DANIEL C. MULVIHILL.
